AIR GIN

Celestino Martinez, San Diego, Tex.

Application June 9, 1936, Serial No. 84,347

3 Claims. (Cl. 19—59)

This invention relates to gins wherein pneumatic means and centrifugal force is employed to bring about separation of the motes and other foreign matter from the lint and the conveying 5 of the latter to condensers. In gins of this character, the pneumatic means causes a vacuum to be developed which affects the centrifugal force and interferes with the separation of the motes from the lint. The present invention has for the 10 primary object the provision of pneumatic means for destroying the vacuum and thereby permit the centrifugal force to function to the maximum for bringing about a thorough separation of the motes from the lint and consequently permit lint 15 to be obtained in a cleaner state.

With these and other objects in view, this invention consists in certain novel features of construction, combination and arrangement of parts to be hereinafter more fully described and 20 claimed.

For a complete understanding of my invention, reference is to be had to the following description and accompanying drawing, in which

Figure 1 is a transverse sectional view illustrating my invention adapted to a gin.

Figure 2 is a fragmentary transverse sectional view drawn on an enlarged scale showing the pneumatic means for destroying the vacuum.

Figure 3 is a fragmentary sectional view taken 30 on the line 3—3 of Figure 2.

Referring in detail to the drawing, the numeral 1 indicates a gin employing centrifugal force for the separation of motes and other foreign matter from the lint and also employing pneumatic means for collecting and conveying the lint from the saws 2 and delivering said 35 lint to condensers (not shown). In gins of this character the velocity of the air employed for conveying the lint from the saws to the condensers is so great as to create a vacuum in the upper portion of the gin. This vacuum affects the centrifugal force preventing the latter from thoroughly separating the motes and foreign matter from the lint. My invention when adapted 40 to a gin of the character described will break up or destroy this vacuum and includes in its construction a duct 3 employed for conveying the lint from the saws to the condensers. The duct 3 is formed in a casing 4 easily adaptable to the gin 1 and the air blast pipe 5 thereof. The casing terminates at the rear of the saws in the form of an elongated nozzle 6. One end of the duct 3 is spaced a considerable distance from the nozzle 6 so that the lint collected by the saws will 50 be removed from the latter by the air blast from

the air blast pipe 5 passing the saws into the duct 3. A duct 7 is formed in the casing 4 and communicates at one end with the air blast pipe 5 and at the other end with the nozzle 6. The ducts 3 and 7 are separated from each other by a wall 8 and one end of the wall 8 terminates within the nozzle 6 and is spaced from a wall 9 of said nozzle to form an air outlet 9' to the nozzle for discharging air blasts against the saws and to the duct 3. This air travels at a high velocity 10 and will develop a vacuum in the upper portion of the gin.

Secured to the nozzle 6 is a hood 10 including a wall 11. The free end of the wall 11 is spaced from the wall 9 providing an intermediate air 15 outlet 12. Formed in the wall 9 is a series of ports 13 permitting some of the air passing through the duct 7 to escape into the chamber 14 formed between the hood 10 and the nozzle. Some of this air escapes by way of the outlet 12 20 having the effect of partially destroying the vacuum. The wall 11 of the hood has a series of ports 15 communicating with the chamber 14 so that some of the air from the chamber 14 may escape cooperating with the air from the 25 intermediate outlet 12 in completely breaking up or destroying the vacuum. The air leaving the outlet 12 is in the form of a column. Also the air leaving the outlet 9' is in the form of a 30 column. The column of air leaving the outlet 9' has a greater velocity than the air leaving the outlet 12. The air leaving the ports 15 are in the form of a series of columns of less velocity than the column of air leaving the outlet 12. The combined area of the outlets 12 and 15 is greater 35 than the combined area of the ports 13 so that when the air passes from the outlets 12 and 15 the velocity of such air will be materially reduced. To further aid in reducing the velocity of air leaving the outlets 12 and 15, the chamber 14 will 40 permit an expansion of the air as it leaves the ports 13. Thus it will be seen that the same air pressure employed for conveying the lint from the saws to the condensers is also employed for creating columns of air to destroy vacuum set up 45 by the column of air used in conveying the lint to the condensers by way of the duct 3.

A device of the character described is simple in construction and operation and may be readily adapted to a gin now in use and will permit the 50 gin to more thoroughly perform its function of separating motes and foreign matter from the lint, consequently permitting lint to be obtained in a cleaner state.

Having described the invention, I claim:

1. A device of the character set forth comprising a casing having a portion thereof formed in a nozzle located adjacent the saws of a gin, ducts formed in said casing and one of said ducts 5 extending from the saws to condensers and the other duct extending from an air blast pipe to the nozzle whereby a column of air may be discharged past the saws for collecting and conveying lint to the condensers, a hood secured to the 10 nozzle and having a wall spaced from one of the walls of the nozzle to form an auxiliary air outlet to develop a column of air of a less velocity than the column of air employed for removing the lint from the saws, said wall of the nozzle 15 having ports to permit air from the air blast pipe to escape to the auxiliary outlet.
2. A device of the character set forth comprising a casing having a portion thereof formed in a nozzle located adjacent the saws of a gin, ducts 20 formed in said casing and one of said ducts extending from the saws to condensers and the other duct extending from an air blast pipe to the nozzle whereby a column of air may be discharged past the saws for collecting and conveying 25 lint to the condensers, a hood secured to the nozzle and having a wall spaced from one of the walls of the nozzle to form an auxiliary air outlet to develop a column of air of a less velocity than the column of air employed for removing the lint from the saws, said wall of the nozzle 30 having ports to permit air from the air blast pipe to escape to the auxiliary outlet, said wall of the hood having a series of ports permitting air to escape therethrough in the form of a series of columns of less velocity than the columns of air before mentioned.

3. A device of the character set forth comprising a casing having a portion thereof formed in a nozzle located adjacent the saws of a gin, ducts formed in said casing and one of said ducts 10 extending from the saws to condensers and the other duct extending from an air blast pipe to the nozzle whereby a column of air may be discharged past the saws for collecting and conveying 15 lint to the condensers, a hood secured to the nozzle and having a wall spaced from one of the walls of the nozzle to form an auxiliary air outlet to develop a column of air of a less velocity than the column of air employed for removing the lint from the saws, said wall of the nozzle 20 having ports to permit air from the air blast pipe to escape to the auxiliary outlet, said wall of the hood having a series of ports permitting air to escape therethrough in the form of a series of 25 columns of less velocity than the columns of air before mentioned, said walls of the nozzle and hood cooperating in forming an air expansion chamber.
